SEALING FLAPS FOR GARMENT OPENINGS
Theodore L. Bailey, Natick, Mass., assignor to the United States of America as represented by the Secretary of the Army

Filed June 22, 1961, Ser. No. 120,889

12 Claims. (Cl. 2—96)

(Granted under Title 35, U.S. Code (1952), sec. 266)

The invention described herein, if patented, may be manufactured and used by or for the Government for governmental purposes, without the payment to me of any royalty thereon.

The invention relates to means for sealing or semi-sealing garment openings to prevent the entry of injurious liquids, gases, dusts, or even mere cold air. The usual garment is either closed by a simple buttoned opening or is provided with an elaborate built-in arrangement of interengaging flaps which add greatly to the cost of the garment but which must be used at all times to close the garment opening irrespective of whether or not it is desirable to use them. For instance, such built-in arrangements retard ventilation and are undesirable in hot weather unless circumstances make use of the sealing means mandatory.

This application is a continuation-in-part of my co-pending application, Serial Number 36,696, filed June 16, 1960, now abandoned.

With the foregoing in view, it is an object of the invention to provide means for at least semi-sealing a garment opening which is readily detachably connected to and removed from a standard garment without modification of the same and without requiring any special tools or skills.

A further object is to provide such a device which is secured to the garment by the usual separable fasteners used to close the garment opening in question.

A further object is to provide an improved means for at least semi-sealing a garment opening which comprises a flat strip at least as long as the opening and which is substantially Z-shaped in cross section to provide opposed bights each receiving an opening-defining free garment edge therein, together with means for securing the folded strip in position.

Other objects and advantages reside in the particular structure of the invention, combination and arrangement of the several elements thereof with each other and/or with a garment, all of which will be readily apparent to those skilled in the art upon reference to the attached drawing in connection with the following specification wherein the invention is shown, described and claimed.

In the drawing:

FIGURE 1 is a plan view of a device according to the invention in unfolded condition and apart from a garment;

FIGURE 2 is fragmentary front elevational view of a garment showing the device of FIGURE 1 applied thereto;

FIGURE 3 is fragmentary transverse sectional view taken substantially on the plane of the line 3—3 of FIGURE 2;

FIGURES 4, 5 and 6 are similar fragmentary front elevational views showing successive steps in the application of the invention to the garment;

FIGURE 7 is a plan view of a modification of the invention in unfolded condition and apart from a garment;

FIGURE 8 is a fragmentary front view of a garment showing the modification applied thereto;

FIGURE 9 is an enlarged fragmentary sectional view taken substantially on the plane of the line 9—9 of FIGURE 8;

FIGURES 10 and 11 are front and rear elevational views respectively of a further modification apart from a garment;

2

FIGURE 12 is a fragmentary front elevational view of a garment showing the modification of FIGURES 10 and 11 applied thereto; and

FIGURE 13 is an enlarged fragmentary sectional view taken substantially on the plane of the line 13—13 of FIGURE 12.

Referring specifically to the drawing wherein like reference characters designate like parts in all views, and referring at first to the species of FIGURES 1—6 inclusive, 10 designates generally a preferred embodiment of the invention which comprises a sheet of flexible and substantially impervious material having a length at least equal to that of the opening which it is intended to seal. In this connection, the sheet shown is for closing the front opening of a garment 11 such as a woman's shirt, coat, blouse or jacket which is closed by the usual row of buttons 12 and the cooperating buttonholes 13. The buttons 12 are attached to the front surface of an inner free edge 14 of the garment, which edge defines one side of the garment opening. The other side of the opening is defined by the overlapping free edge 15 in which the buttonholes 13 are formed.

The seal 10 includes an outer margin 17, and inner margin 16 together with top and bottom edges 18 and 19 respectively. Inner and outer rows of buttonholes 20 and 21 respectively are formed in the seal adjacent the inner margin 16 and parallel thereto. Two laterally spaced buttonholes 22 and 23 are formed near the top edge 18 respectively in alignment with the rows of buttonholes 20, 21. Two vertically spaced buttonholes 24 and 25 are formed in the seal 10 adjacent the inner margin 16, the buttonhole 24 being also adjacent the top edge 18 and in lateral alignment with the buttonholes 22 and 23. The buttonhole 25 is in lateral alignment with two of the lowermost buttonholes 22 and 23.

In use the device is positioned as best seen in FIGURE 3 and is applied to the garment in the manner illustrated in FIGURES 4, 5 and 6. Thus, referring at first to FIGURE 4, the garment is unbuttoned and the seal 10 is inserted under the free edge 14 with the outer margin 17 extending beyond such free edge. The outer margin 17 is then turned backward to overlie the garment free edge 14 and the buttons 12 are buttoned through the upper buttonhole 22 and those inner buttonholes 20 which register with the buttons 12. In this connection a number of extra buttonholes 20 and 21 have been provided to accommodate garments other than that shown and having varying spacings of the buttons.

In the next step, FIGURE 5, the garment outer free edge 15 is buttoned to the buttons 12. Thereafter, FIGURE 6, the outer margin 17 is again reversely directed to overlie the free edge 15 and dispose the outer buttonholes 23 and 21 in registry with the buttons 12 to which they are buttoned to complete the seal. The completed arrangement, FIGURE 3 is a substantially S- or Z-shaped strip which provides oppositely directed inner and outer bights 26 and 27 which respectively receive therein the inner and outer free edges 14 and 15. Thus, the arrangement provides a semi-seal for the garment which is highly effective to retard the passage through the buttoned opening of air, gas, liquids, dusts and other undesirable matter. At the same time, the device is readily applicable to a standard garment without special skill, tools or knowledge. It is equally easily detached from the garment.

60 The buttonholes 24 and 25 are utilizable with another garment as are those buttonholes 20 and 21 not shown as being used. Thus, the arrangement shown may be considered a universal seal in that it is used on the military shirt shown as the garment, is likewise usable on the uniform coat or blouse, and may also be used on a military overcoat and on certain types of jackets.

70 The modification illustrated in FIGURES 7, 8 and 9

shows a species of the invention which is adapted to be applied to a pair of trousers 30 of the type having a buttoned fly front comprising an inner fly 31 having a row of buttons 32 fixed thereon and a outer fly 33 formed with a row of buttonholes 34 for the buttons 32 which in turn, are covered by the usual flap 35 which is secured to the outer fly 33 to conceal the buttonholes and the buttons. This species of the invention comprises a substantially semi-oval sheet 36 of impervious material having a straight top edge 37 and a curved side and bottom edge 38. A pair of tie tapes 39 are secured to each end of the top edge 37 for a purpose to be apparent. A vertical row of buttonholes 40 is formed in the sheet 36 generally centrally thereof.

In use, the trouser fly is unbuttoned and the sheet 36 is applied to the inner surface of the inner fly 31 with the upper edge 37 flush with the upper edge of the waistband. The adjacent pair of tapes 39 are now tied to an adjacent belt loop 41. Sheet 36 is now folded over the free edge of the inner fly 31 so that the buttonholes 40 register with and are buttoned to buttons 32 of such fly. The outer fly 33 is now buttoned to the buttons 32 in the usual manner. The remainder of sheet 36 is now folded over the free edge of the outer fly 33 so as to overlie the flap 35. The other pair of tapes 39 are now tied to an adjacent belt loop 42 of the trousers. Of course, securing means other than the tapes 39 are contemplated but these have the advantage of requiring no modification of the trousers 30.

As in the species of FIGURES 1-6, the device in use provides inner and outer bights 43 and 44 respectively which receive therein the free edges of the inner and outer flies 31 and 33 so as to bar the entry of foreign matter through the closure.

The modification of FIGURES 10-13 is very similar to the species of FIGURES 1-6. Here however, the sheet 45 has an inner edge 46 prefolded so as to underlie the main body of the sheet and an inner row of buttonholes 48. The lower edge of the folded edge 46 is bar-tacked as at 47, FIGURE 11 or otherwise suitably secured to the lower edge of the main body of sheet 45 to hold the edge 46 in such pre-folded position. As in the first described species there is an outer row of buttonholes 49 provided in the sheet 45. Also, inner and outer top buttonholes 50 and 51 are provided. Inner bight 53 is thus preformed.

In use, this species is applied to a shirt 54 or the like by inserting the inner free edge 55 of the shirt into the pocket formed by the pre-folded edge portion 46 of the sheet 45. The buttonhole 50 and such of the buttonholes 48 as register with the shirt buttons 56 are then buttoned and the outer free edge 57 of the shirt is buttoned to the buttons 56 by the usual buttonholes 58. The exposed edge portion of the sheet 45 is now folded over the free outer edge 57 of the shirt to form the outer bight 59 and to register the appropriate outer buttonholes 51, 49 with the buttons 56 to which they are secured, as before.

It is to be understood that the specific embodiments shown and described hereinabove may be varied considerably within the spirit and scope of the invention as claimed hereinafter. Thus, while there have been shown and described what is now thought to be the preferred species of the invention, it should be understood that the same is susceptible of still other forms and expressions. Therefore, it is not my intention to limit myself to the precise structures shown and described hereinabove but only as hereinafter claimed.

I claim:

1. The combination with a garment having an opening defined by overlapping inner and outer garment free edges, at least one individual separable fastener element on each edge for securing said free edges together; of a flexible flap for sealing said opening, said flap being at least as long as said opening, said flap having an inner margin underlying said inner free edge, said flap having an integral middle portion which is reversely directed to ex-

10 tend between said inner and outer free edges and provide an inner bight receiving said inner free edge therein, said middle flap portion being formed with a hole therethrough in registry with said fastener elements, said flap having an integral outer margin which is reversely directed relative to said middle portion to overlie said outer free edge and provide an outer bight receiving said outer free edge therein, and means readily detachably securing said outer flap margin to one of said separate fastener elements in said overlying relation to said outer free edge.

15 2. The combination with a garment having an opening defined by overlapping inner and outer edge portions, said outer edge portion being formed with a buttonhole, said inner edge portion having a button secured thereto for passage through said buttonhole to connect said edge portions together, of a flexible flap for sealing said opening, said flap having an inner margin underlying said inner edge portion and an outer margin overlying said outer edge portion, said flap having a central portion disposed between said inner and outer edge portions, there being integral oppositely directed bight portions connecting said inner and outer margins to said central portion across said edge portions, said central flap portion being formed with a buttonhole in registry with said first named buttonhole and passing said button therethrough, and means for readily detachably securing said outer margin to said outer edge portion of said garment.

20 3. The combination with a garment having an opening defined by overlapping inner and outer edge portions, said outer edge portion being formed with a buttonhole, said inner edge portion having a button secured thereto for passage through said buttonhole to connect said edge portions together, of a flexible flap for sealing said opening, said flap having an inner margin underlying said inner edge portion and an outer margin overlying said outer edge portion, said flap having a central portion disposed between said inner and outer edge portions, there being integral oppositely directed bight portions connecting said inner and outer margins to said central portion across said edge portions, said central flap portion being formed with a buttonhole in registry with said first named buttonhole and passing said button therethrough, and said outer flap portion being formed with a buttonhole receiving said button therethrough to readily detachably secure said outer margin to said outer edge portion of said garment.

25 4. In a body garment, the combination with a garment opening defined by overlapping inner and outer free edges; of sealing means providing at least a semi-seal for said opening, said sealing means comprising a substantially flat S-shaped body of sheet material having a length substantially the same as the length of said opening, said sealing means including oppositely directed inner and outer bights respectively receiving therein said inner and outer free edges, and means for readily detachably securing said sealing means to said garment.

30 5. In a body garment, the combination with an elongated opening defined by overlapping inner and outer free edges, said free edges being provided with registering rows of buttons and buttonholes for detachably securing said free edges together; of sealing means providing at least a semi-seal for said opening, said sealing means comprising a substantially flat S-shaped body of flexible sheet material having a length substantially the same as that of said opening, said sealing means including oppositely directed inner and outer bights respectively receiving therein said inner and outer free edges, and said sealing means being formed with at least one row of buttonholes in registry with said row of buttons and receiving the same therethrough whereby to provide means for securing said sealing means to said garment in sealing relation to said opening.

35 6. In a body garment, the combination with an elongated opening defined by overlapping inner and outer free edges, said free edges being provided with register-

ing rows of buttons and buttonholes for detachably securing said free edges together; of sealing means providing at least a semi-seal for said opening, said sealing means comprising a substantially flat S-shaped body of flexible sheet material having a length substantially the same as that of said opening, said sealing means including oppositely directed inner and outer bights respectively receiving therein said inner and outer free edges, and said sealing means being formed with two superposed rows of buttonholes in registry with said row of buttons and receiving the same therethrough to provide means for detachably securing said sealing means to said garment in sealing relation to said opening.

7. In a body garment, the combination with an elongated opening defined by overlapping inner and outer free edges, there being a row of buttons on said inner free edge outwardly thereof, there being a registering row of buttonholes formed in said outer free edge for detachably securing said free edges together; of sealing means providing at least a semi-seal for said opening, said sealing means comprising a flexible flap having a length at least as great as that of said opening, said flap being formed with a longitudinal Z-fold to provide inner and outer margins connected by a central portion providing oppositely disposed inner and outer bights respectively receiving therein said inner and outer free edges, said central portion and said outer margin being formed with registering rows of buttonholes, at least some of said buttonholes of each of said last named rows being in registry with said row of buttonholes on said outer free edge, said buttons being passed through the registering buttonholes of said three rows of the same to readily releasably close said opening and readily detachably secure said flap across said opening in sealing relation thereto, and said buttonholes of said flap not registering with those of said garment adapting said flap for use with other garments having different buttonhole arrangements.

8. In a nether garment including a waistband having belt loops thereon, the combination with a fly opening through said waistband, said fly opening being defined by inner and outer flies having free edges, there being a belt loop on each fly; of sealing means providing at least a semi-seal for said opening, said sealing means comprising a substantially flat S-shaped body of sheet material having a length corresponding substantially to that of said opening, said sealing means including inner and outer bights respectively receiving therein said free edges of said inner and outer flies, and securing means for readily detachably securing said body to said belt loops.

9. The combination of claim 8, wherein said body of sheet material includes inner and outer top free edges in

substantially flush relation with said waist band, and said securing means comprising tie tapes on said free top edges.

- 5 10. The combination with a garment having an opening defined by overlapping inner and outer garment free edges, at least one individual separable fastener element on each edge for securing said free edges together; of a flexible flap for sealing said opening, said flap being at least as long as said opening, said flap having an inner margin underlying said inner free edge, said flap having an integral middle portion which is reversely directed to extend between said inner and outer free edges and provide an inner bight receiving said inner free edge therein, said middle flap portion being formed with a hole therethrough in registry with said fastener elements, said flap having an integral outer margin which is reversely directed relative to said middle portion to overlie said outer free edge and provide an outer bight receiving said outer free edge therein, means readily detachably securing said outer flap margin in said overlying relation to said outer free edge, said inner margin and said middle portion of said flap having free lower edges, and means securing said lower edges together.
- 15 20 25 30 35

11. In a body garment, the combination with a garment opening defined by overlapping inner and outer free edges; of sealing means providing at least a semi-seal for said opening, said sealing means comprising a substantially flat S-shaped body of sheet material having a length substantially the same as the length of said opening, said sealing means including oppositely directed inner and outer bights respectively receiving therein said inner and outer free edges, means for readily detachably securing said sealing means to said garment, said body having three superposed lower edges, and means securing at least two of said lower edges together.

- 40 45 50
12. In a body garment, the combination with a garment opening defined by overlapping inner and outer free edges; of sealing means providing at least a semi-seal for said opening, said sealing means comprising a substantially flat S-shaped body of sheet material having a length substantially the same as the length of said opening, said sealing means including oppositely directed inner and outer bights respectively received therein said inner and outer free edges, means for readily detachably securing said sealing means to said garment, said body having inner, middle and outer lower edges, and means securing at least said inner and middle lower edges together.
